UNITED STATES PATENT OFFICE

WILLIAM E. SWIFT, OF GARY, INDIANA, ASSIGNOR OF ONE-THIRD TO CYRIL E. PAULDING AND ONE-THIRD TO JOSEPH E. LA BARGE, BOTH OF GARY, INDIANA

DESIGN FOR A GRAVE MARKER

Application filed September 9, 1931. Serial No. 41,052. Term of patent 3½ years.

To all whom it may concern:

Be it known that I, WILLIAM E. SWIFT, a citizen of the United States of America, residing at Gary, in the county of Lake and State of Indiana, have invented a new, original, and ornamental Design for a Grave Marker, of which the following is a specification, reference being had to the accompanying drawings, forming a part thereof.

I claim:

The ornamental design for a grave marker as shown.

WILLIAM E. SWIFT.
